UNITED STATES PATENT OFFICE

PAUL E. COLLETTE, OF RAVENNA, OHIO, ASSIGNOR TO THE OAK RUBBER COMPANY, OF RAVENNA, OHIO, A CORPORATION OF OHIO

DESIGN FOR A TOY BALLOON

Application filed December 2, 1931. Serial No. 41,939. Term of patent 7 years.

To all whom it may concern:

Be it known that I, PAUL E. COLLETTE, a citizen of the United States, residing at Ravenna, in the county of Portage and State of Ohio, have invented a new, original, and ornamental Design for a Toy Balloon, of which the following is a specification, reference being had to the accompanying drawings, forming a part thereof.

In the drawings Fig. 1 is a side view of the toy balloon embodying the design. Fig. 2 is a rear end view of that shown in Fig. 1.

I claim:

The ornamental design for a toy balloon substantially as shown.

PAUL E. COLLETTE.
